UNITED STATES PATENT OFFICE.

FRANK E. FECK, OF MORGANTOWN, WEST VIRGINIA.

DESIGN FOR A PITCHER OR SIMILAR ARTICLE.

Application filed May 16, 1923. Serial No. 6,169. Term of patent 14 years.

To all whom it may concern:

Be it known that I, FRANK E. FECK, residing at 506 Beechurst Avenue, Morgantown, West Virginia, have invented a new, original, and ornamental Design for a Pitcher or Similar Article, of which the following is a specification, reference being had to the accompanying drawing, forming part hereof, in which the figure is a perspective view of a pitcher showing my new design.

I claim:

The ornamental design for a pitcher or similar article as shown.

FRANK E. FECK.
